UNITED STATES PATENT OFFICE.

THADIOUS VENSON ELLIOTT, OF COLUMBIA, PENNSYLVANIA, ASSIGNOR
OF ONE-HALF TO JOHN B. HUTCHINSON, OF COLUMBIA, PENNSYLVANIA.

GAS-CONSUMER.

SPECIFICATION forming part of Letters Patent No. 746,936, dated December 15, 1903.

Original application filed July 3, 1902. Renewed November 17, 1903. Serial No. 181,553. (No model.)

To all whom it may concern:

Be it known that I, THADIOUS VENSON ELLIOTT, a citizen of the United States, residing at Columbia, in the county of Lancaster and 5 State of Pennsylvania, have made certain new and useful Improvements in Gas-Consumers, of which the following is a specification.

My invention is an improvement in gas-consuming furnaces, and particularly in steam-boiler furnaces, and has for an object to provide a novel construction whereby the gases escaping from the furnace may be returned directly to the fire and be consumed, thereby 15 avoiding the loss of the gas and economizing the heat units secured in the operation of the furnace; and the invention consists in the novel constructions and combinations of parts constituting the gas-returning device and in 20 the combination thereof with a draft device located in the stack by which to secure the desired draft in the use of the apparatus, as will be claimed.

In the drawings, Figure 1 is a vertical longitudinal section of a furnace provided with my invention. Fig. 2 is a front elevation of the the boiler and gas-consuming device, the brick-work of the furnace being omitted. Fig. 3 is a detail enlarged elevation, parts being broken 30 away and parts shown in section, representing the nozzle of the steam-injector device. Fig. 4 shows a somewhat different construction from that shown in the other figures. Fig. 5 is a detail sectional view showing the air-valve 35 used on the upper ends of the upright connecting-pipes.

By my invention I provide means for collecting or catching the gases which escape from the furnace and for returning same by 40 means of a forced draft into the furnace, where they will be consumed. In the application of the invention to return-flue boilers, such as shown at A in Figs. 1 and 2, I provide for catching the gases discharged through the 45 upper flues, as being of less specific gravity than the other products of combustion they will pass naturally through the upper flues. I thence return the gases to the furnace and discharge them below the grate-bars, whence 50 they will pass up through the fire and be con-

sumed, thus increasing the heat of the fire and economizing the combustion by securing a combustion of all the combustible parts of the fuel. To this end I provide a collecting pipe or pipes B, closed at one end at B' and 55 provided throughout their lengths on their under sides and sides adjacent to the discharge end of the boiler-flues with perforations b of such size and number as to receive the gases discharged from the upper flues of 60 the boiler and deliver same to the upright return-pipes C, with which the pipes B connect at their ends opposite their closed ends B. The pipes C preferably extend above their connection with the pipes B and are 65 provided at their upper ends with valves D, which may be adjusted to regulate the amount of air admitted to the pipe C to mingle with the steam discharged by the injector F at a point below the connection of the 70 pipes B with the pipes C, such injectors E discharging downwardly and forcing the gases down to deliver into the discharge-pipes F and G, arranged below the grate-bars H of the furnace H. The pipe F extends between 75 and connects the lower end of the opposite pipes C, and the pipes G connect with the pipes C and F and extend longitudinally beneath the grate, as shown in Fig. 1. The valve D is in the form of a cap closed at its 80 upper end, fitting on the upper end of the pipe C and having a longitudinal slot D', which by the adjustment of the cap up or down may be regulated to admit more or less air to the pipe C, as desired. The pipes F 85 and G are perforated to permit the discharge of the gases, which will pass directly to the fire, as indicated in Fig. 1.

In directing the steam-pipes E' to the injectors E it is preferred to provide such pipes 90 with a drop portion or bend E², so the valves E³ for controlling said pipes may be located in convenient reach from the floor or bed of the furnace.

In Fig. 2 I show two side pipes C and a collecting cross-pipe B, uniting with each of said side pipes C; but it will be understood that where desired I may employ the single arrangement of upright pipes, as shown at C' in Fig. 4, and connect both of the perforated 95 100

cross collecting-pipes B² with the inner upright connecting-pipe C', as shown in said Fig. 4.

In operation it will be understood the valves 5 D and the valves E³ may be regulated to secure the desired supply of steam and air, which will operate efficiently to produce the necessary suction in the collecting-pipes B to draw thereinto the gases discharged from the 10 upper flues of the furnace and to force said gases through the pipe C into the discharge-pipes F and g, whence they will pass to the furnace. It will be noticed that by the described construction I provide a return force 15 draft by which to collect the gases and to return the same to the furnace. It will also be noticed that this return-draft is exerted on the gases discharged from the upper flues of the boiler. Now to prevent any checking of 20 the draft of the furnace and to insure the proper operation of the furnace, as desired, I provide a draft device I in the stack A' of the furnace in such manner as to produce a force draft which will catch the products of 25 combustion discharged from the lower flues of the boiler, passing upwardly and outwardly around the collecting-tubes B, and deliver such products out of the stack. It will therefore be noticed that my invention includes a 30 draft device operating upon the stack in such manner as to secure the desired draft upon the furnace in connection with the force return draft for delivering the gases back to the furnace. The specific draft device 35 I show is not in its specific construction claimed herein, but forms the subject-matter of a separate application for patent executed by me of even date herewith, and it will be understood that in the practicable operation 40 of the present invention I may substitute other forms of draft-inducing devices from that shown at I in Fig. 1 without departing from the broad principles of the present invention, although the draft device I, as shown 45 in Fig. 1, is preferred.

My draft-return devices, it will be noticed, comprise in the form shown in Fig. 2 the cross collecting-tubes extending in opposite directions from the opposite upright connecting-tubes, in which operate the injectors and which connecting-tubes discharge at their 50 lower ends to the cross discharge-tube F and the opposite longitudinal discharge-tubes G, which extend between the grate of the furnace and discharge the gas to the furnace in a finely-divided condition, thus insuring the proper combustion of the gases in the operation of the furnace. It will also be noticed that the pipes C extend sufficiently above the 55 injectors E to form short stacks through 60

which the air will be drawn by the injectors when the steam is turned on.

In operation it will be noticed the gases will be hived or collected in the pipes B and will be conducted thence to the furnace, 65 where they will be consumed, my invention including, therefore, broadly, means for hiving the unconsumed gases discharged from the furnace and means for returning the gases so hived to the furnace for consumption 70 therein.

Having thus described my invention, what I claim as new, and desire to secure by Letters Patent, is—

1. A gas-consuming device substantially 75 as herein described, comprising in combination with a return-flue boiler and the furnace thereof, the opposite upright connecting-tubes provided with valves for controlling the inlet of air and below said valves with downwardly-directed injectors, the cross collecting-tubes perforated to receive the gases and extending in opposite directions from the opposite connecting-tubes inwardly and across the front of the boiler, adjacent to the 80 upper flues thereof, and a perforated cross-tube and longitudinally-extending tubes connected with the lower ends of the upright connecting-tubes, and extending beneath the grate of the furnace, and the steam-pipes for 85 the injectors, having drop portions and valves therein, substantially as set forth.

2. The combination in a gas-consuming device, of the opposite upright connecting-pipes, the laterally-extending collecting-pipes 95 leading in opposite directions inwardly from their respective connecting-pipes, the latter being provided with extensions above the collecting-pipes and with valves controlling said extensions, the steam-injector devices discharging to the connecting-pipes, the cross discharge-pipes extending between the connecting-pipes at the lower ends thereof, and the longitudinally-extending discharge-pipes, 100 substantially as set forth.

3. A gas-consuming device comprising the opposite upright connecting-tubes provided with valves for controlling the inlet of air, injectors below said valves, the cross collecting-tubes extending in opposite directions 110 from the opposite connecting-tubes inwardly, a perforated cross-tube and longitudinally-extending tubes connected with the lower ends of the connecting-tubes, and the steam-pipes for the injectors, substantially as set 115 forth.

THADIOUS VENSON ELLIOTT.
